TOGGLE CLAMP

Edward Zazdrzyk, Brooklyn, N. Y.

Application July 11, 1952, Serial No. 298,241

3 Claims. (Cl. 81—88)

1

This invention relates to clamps or wrenches and more particularly to a clamp or wrench having adjustable toggle mechanism for closing its jaws.

It is among the objects of the invention to provide an improved clamp or wrench of the snap-on type having relatively movable jaws and adjustable toggle mechanism for closing its jaws on a work piece; which includes spring means resiliently urging the jaws in a separating direction and spring means cushioning the jaw closing force exerted on the jaws by the toggle mechanism; which has a handle which completely covers the toggle mechanism and springs when the jaws are in closed position to protect the hands of a person using the device from injury; which has two adjustments for the toggle mechanism, one of which controls the spacing of and the pressure between the jaws and the other of which controls the locking of the toggle mechanism and can be set to prevent the toggle mechanism from locking when the jaws are closed, so that the device can be used as a cutting or crimping tool with selected jaw pressures; and which is simple and durable in construction, economical to manufacture, easy to use, and neat and attractive in appearance.

Other objects and advantages will become apparent from a consideration of the following description and the appended claims in conjunction with the accompanying drawings wherein:

Figure 1 is a side elevational view of the clamp with the clamp jaws closed;

Figure 2 is a view similar to Figure 1 showing the clamp jaws open;

Figure 3 is a rear elevational view of the device;

Figure 4 is a longitudinal cross sectional view on the line 4—4 of Figure 3;

Figure 5 is a transverse cross sectional view on the line 5—5 of Figure 1; and

Figure 6 is a transverse cross sectional view on the line 6—6 of Figure 1.

With continued reference to the drawings, the device comprises an elongated back bar 10 of rectangular cross sectional shape having a fixed jaw 11 projecting perpendicularly therefrom at one end thereof and a lug 12 projecting perpendicularly therefrom at the other end thereof and in the same direction as the fixed jaw 11. The lug 12 has near its end remote from the back bar 10 a tapped hole 13, the longitudinal center line of which is substantially parallel to the longitudinal center line of the back bar.

2

A first slide 14 is mounted on the back bar 10 adjacent the fixed jaw 11 for movement longitudinally of the back bar and includes a movable jaw 15 positioned in opposition to the fixed jaw 11. This first slide comprises a substantially rectangular body 16 of sheet metal bent to U-shaped form and a flat block 17 of substantially rectangular shape disposed between the sides of the body 16 and spaced from the intermediate or bight portion of the body 16 to provide a space slidably receiving the back bar 10, the sheet metal body 16 being secured to the block 17 by suitable means, such as the rivets 18. Both the body 16 and the block 17 are extended at the corner 15 of the slide remote from the back bar 10 and adjacent the fixed jaw 11 to provide a movable jaw extension which extends outwardly to the distal end of the fixed jaw 11.

A second slide 20 is slidably mounted on the back bar 10 between the slide 14 and the lug 12 and also includes a sheet metal body 21 of rectangular shape bent to U-shaped cross section, and a flat block 22 disposed in the body 21 and secured thereto by the rivets 23 and 24. The block 22 is spaced from the intermediate or bight portion of the body 21 to provide a space slidably receiving the back bar 10 and the block 22 is provided with a slot 25 disposed intermediate the width thereof and extending from a location adjacent the end of the block nearest the lug 12 to the other end of the block where it is beveled or flared outwardly, as indicated at 26 and 27. The sides of the body 21 are bowed outwardly to partly cylindrical shape at the opposite sides of the notch 25 in the block 22 to provide in the slide 20 a socket of substantially cylindrical shape closed at its end adjacent the lug 12 and opening to the end of the slide 20 adjacent the slide 14.

An adjusting screw 28 is threaded through the 40 tapped hole 13 in the lug 12 and has a thumb-wheel 29 on the end thereof at the outer side of the lug. At its other end the screw is rotatably received in a hole 30 in the block 22 at the closed end of the socket 31 and this end of the screw is enlarged at the closed end of the socket, as indicated at 32, so that the screw cannot pull out of the block 22. An abutment plate 33 is mounted in the slot 25 at the closed end of the latter and bears against the adjacent end of the screw, so that the screw cannot move into the socket or slot and the slide 20 will be positively moved along the back bar 10 in one direction or the other when the screw 28 is rotated in the corresponding direction.

55 A compression spring 35 is disposed in the

socket 31 and bears at one end against the abutment plate 33. A movable abutment 36 is disposed in the socket near the open end of the latter and bears against the adjacent end of the compression spring 35 and a link 37 is pivotally connected at one end to the movable abutment 36 and extends from this movable abutment toward the slide 14.

A tension spring 38 extends along the inner side of the back bar 10 and is connected at one end to the slide 14 and at its other end to the slide 20 and acts to resiliently urge the slide 14 toward the slide 20 and the movable jaw 15 away from the fixed jaw 11 of the device.

A handle 40 is pivotally connected at one end to the slide 14 at the corner of this slide remote from the back bar 10 and the fixed jaw 11 and comprises a sheet metal body bent to U cross sectional shape and having intermediate its length a portion of maximum width. The portion of maximum width is nearer the end of the handle connected to the slide 14 than to the other end of the handle and the handle tapers at its side remote from the back bar 10 in both directions away from the portion of maximum width. At its end pivotally connected to the slide 14 the handle is provided with a pair of outwardly extending apertured lugs which are disposed one at each side of the slide 14 and pivotally secured to the latter by one of the rivets 13 or by a pivot pin substituted for one of these rivets. A guideway 43 comprising two pair of spaced apart and substantially parallel ribs, one pair of which extends along the inner surface of one side, and the other pair of which extends along the inner surface of the other side of the handle, extend transversely of the handle at the portion of maximum width and is disposed substantially perpendicular to the edge or side of the handle adjacent the back bar 10. At the end of the guideway remote from the back bar 10 the handle is provided with a tapped hole 44 and an adjusting screw 45 is threaded through this hole and carries a thumbwheel 46 on its end at the outer side of the handle. A slide block 47 is slidably mounted in the guideway 43 and pivotally connected to the adjacent end of the adjusting screw 45 for movement longitudinally of the guideway upon rotation of the adjusting screw and the link 37 is pivotally connected at its end remote from the spring abutment 36 to the slide block 47.

With this arrangement, and with the adjusting screw 45 threaded inwardly of the handle to its maximum extent, the device acts as a toggle clamp. When the distal end of the handle is moved away from the end of the back bar 10 carrying the lug 12 the slide 14 carrying the movable jaw is moved away from the fixed jaw and when the distal end of the handle is forced toward the lug 12, the movable jaw is moved toward the fixed jaw as the toggle linkage including the handle and the link 37 is straightened. When the pivotal connection between the link 37 and abutment 47 passes the line extending through the axes of the pivotal connection between the handle and the slide 14 and between the link and the spring abutment 36 to the side of this line adjacent the back bar 10, the toggle mechanism is locked in jaw closing position. The spacing between the jaws, when the toggle mechanism is locked, is controlled by adjustment of the adjusting screw 28 and the pressure exerted between the jaws is also controlled by this adjusting screw, since movement of the slide 20 by the adjusting screw will change the loading on

the compression spring 35 when the jaws are closed on a work piece.

Under some operating conditions it is desirable that the toggle mechanism should not lock when the handle is brought to its limiting position adjacent the back bar 10, and locking of the toggle mechanism under these conditions can be prevented by threading the adjusting screw 45 outwardly of the handle 40 until the pivotal connection between the slide block 47 and the link 37 does not cross the line extending through the axes of the pivotal connections between the handle and the slide 14 and the link 37 and spring abutment 36. Under this latter condition the tool may be used as a cutting or crimping tool, and in the condition in which the toggle mechanism locks, it may be used as a clamp or wrench or a pair of locking pliers.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. An adjustable clamp comprising an elongated back bar having a fixed jaw projecting perpendicularly therefrom at one end thereof, a first slide surrounding said back bar and movable longitudinally thereof adjacent said fixed jaw, said first slide including a movable jaw disposed in opposition to said fixed jaw, a second slide mounted on said back bar adjacent the other end of the latter and including a socket, a lug projecting from said back bar at said other end of the latter in the same direction as said fixed jaw and having a tapped hole near the distal end thereof, an adjusting screw threaded through the tapped hole in said lug and connected at one end to said second slide for adjustably moving the latter longitudinally of said back bar, said socket being closed at the end thereof adjacent said lug, a compression spring in said socket, a movable abutment in said socket at the end of said compression spring remote from said lug, a handle pivotally connected at one end to said first slide and extending from said first slide past said second slide, said handle having a guideway extending transversely thereof and a tapped hole therein at one end of said guideway, a second adjusting screw threaded through the tapped hole in said handle and extending along said guideway, a slide block slideable along said guideway and connected to the adjacent end of said second adjusting screw, and a link pivotally connected at one end to said movable abutment and at its other end to said slide block.

2. An adjustable clamp comprising an elongated back bar having a fixed jaw projecting perpendicularly therefrom at one end thereof, a first slide surrounding said back bar and movable longitudinally thereof adjacent said fixed jaw, said first slide including a movable jaw disposed in opposition to said fixed jaw, a second slide mounted on said back bar adjacent the other end of the latter and including a socket, a lug projecting from said back bar at said other end of the latter in the same direction as said fixed jaw and having a tapped hole near the distal end

thereof, an adjusting screw threaded through the tapped hole in said lug and connected at one end to said second slide for adjustably moving the latter longitudinally of said back bar, said socket being closed at the end thereof adjacent said lug, a compression spring in said socket, a movable abutment in said socket at the end of said compression spring remote from said lug, a handle pivotally connected at one end to said first slide and extending from said first slide past said second slide, said handle having a guideway extending transversely thereof and a tapped hole therein at one end of said guideway, a second adjusting screw threaded through the tapped hole in said handle and extending along said guideway, a slide block slideable along said guideway and connected to the adjacent end of said second adjusting screw, and a link pivotally connected at one end to said movable abutment and at its other end to said slide block, said handle being of U-shaped cross section and enclosing said guideway and covering said link, said spring and said second slide when positioned along said back bar.

3. In an adjustable clamp having a back bar with a fixed jaw projecting therefrom, a movable jaw slidably mounted on said back bar for movement toward and away from said fixed jaw,

and an abutment spaced from the side of said movable jaw remote from said fixed jaw and movable to selected positions of adjustment along said back bar, toggle means for moving said movable jaw toward and away from said fixed jaw comprising a handle pivotally connected at one end to said movable jaw, a block mounted on said handle and movable to selected positions of adjustment transversely of said handle, and a link pivotally connected at one end to said abutment and at its other end to said block.
